(57) **CLAIM**

The ornamental design for a safety rail for a marine vessel, as shown and described.

DESCRIPTION

FIG. 1 is a front perspective view of a safety rail for a marine vessel.

FIG. 2 is a front view thereof.

FIG. 3 is a rear view thereof.

FIG. 4 is an end view thereof.

FIG. 5 is an opposite end view thereof.

FIG. 6 is a top view thereof; and,

FIG. 7 is a bottom view thereof.

The broken lines are for the purpose of illustrating portions of the safety rail that form no part of the claim. The dash-dot broken lines immediately adjacent the shaded areas represent the bounds of the claim. None of the broken lines form a part of the claimed design.
